UNITED STATES PATENT OFFICE.

FRANCIS JOHN COLE AND GEORGE BLAGDEN HAZLEHURST, OF BALTIMORE,
MARYLAND.

OIL-CUP.

SPECIFICATION forming part of Letters Patent No. 478,224, dated July 5, 1892.

Application filed March 5, 1892. Serial No. 423,945. (No model.)

To all whom it may concern:

Be it known that we, FRANCIS JOHN COLE and GEORGE BLAGDEN HAZLEHURST, citizens of the United States, and residents of the city 5 of Baltimore, State of Maryland, have invented certain new and useful Improvements in Oil-Cups, of which the following is a specification.

Our invention consists in a crank-pin oiler 10 for locomotives or other engines or machinery, where the part to be lubricated is in rotary motion and the supply of oil is admitted to the bearing by the vibration of a rod or other similar part within the oiler, whereby a valve 15 is intermittently opened and closed.

In the drawings, Figure 1 is a vertical section through the oil-cup. Fig. 2 is a plan of the exterior of the oil-cup. Fig. 3 is an elevation of the adjustable cap for regulating 20 the feed. Fig. 4 is a plan of the same. Fig. 5 is an elevation of the central shank or valve-case with the oil-inlet shown in full. Fig. 6 is a side elevation of the same turned at an angle of ninety degrees with the previous position. Fig. 7 is a plan of the same.

A is a cup arranged to contain oil.

B is a cap or cover screwed into the top of the cup.

D is an independent stem or shank containing the spindle and provided on its end 30 with a screw-thread for fastening the cup on the part to which it is to be attached, and having a thread on its upper end upon which is screwed the adjustable cap for regulating 35 the feed.

E is a channel-way or hole cut through the center of said stem transversely and of a size larger than the valve-stem on the interior of the shank.

F is a hole through the center of the stem D of smaller size below the transverse hole E than above it, and having a valve seated upon its upper end at the point where it enters the hole E from below.

G is a valve-stem or vibrating spindle which forms a valve at its lower end. The lower portion is smaller than the upper part and enters the hole F, which is below the oil-inlet E, while its upper portion is larger and about 50 fills the larger hole in the upper portion of

said stem. At the point where the spindle narrows there is a shoulder or valve which fits the valve-seat at the upper end of the oil-inlet F and when in position upon it closes the oil-entrance to the bearing.

55

H is a thread upon the upper end of the stem D, upon which is screwed an adjustable cap J, which is cylindrical at its lower portion, open at the top, and having a yoke K across the top connecting the two sides. This 60 cap may of course be made of any other shape so long as it has an internal screw. This yoke is quite high, so as to stand considerably above the cylindrical portion of the cap. The top of the valve stem or rod G rests 65 or stands just below the under side of the yoke K, and the amount of motion permitted to the valve-stem is dependent upon the position of the cap and its yoke. The cylindrical portion of the cap J is split on one side 70 at the point marked L. This slit is somewhat open, so that by pinching the cylindrical portion of the cap it may be made to fit tightly upon the thread H, and be made to retain its position while the machinery is in operation. 75

The operation of the device is as follows: When the oil-cup is to be attached to a piece of machinery—such as a locomotive, for instance—the oil-cup is put on and the spindle 80 screwed through its bottom into the hole provided for it. A specially-constructed wrench having a deep socket is then placed over the shank and it is screwed down firmly onto its seat. When this is done, it will be seen that it will be impossible to remove the oil-cup 85 without taking it apart and also without this special wrench to take hold of the stem. This difficulty avoids the loss of these oil-cups by theft, which frequently happens in the forms which can be easily removed with the ordinary wrench. The spindle or valve-stem is then placed in the center of the stem with its shoulder bearing upon the valve-stem. The cap is then screwed on, the threads fitting 90 tightly upon the thread H on the upper end 95 of the stem D, so as to hold it rigidly in any position at which it may be placed. It should be so adjusted that a small amount of play, from one thirty-second to one-sixteenth of an inch, be left between the top of the spindle 100

and the under side of the yoke, so as to permit any desired amount of play in the valve-spindle. The cup is then filled with oil and the cap screwed in place. When the machinery is in rotary motion the rapid up-and-down motion of the crank will cause a similar throw of the spindle and permit oil to flow through the transverse channel-way E, through the valve and the inlet-opening F to the bearing. The feed of the spindle may be easily adjusted by a simple turn or part turn of the adjustable cap and the amount of feed of the spindle can be seen at a glance upon taking off the top of the oil-cup. The transverse hole E, being at the bottom of the cup instead of the top, as is usual in many cases, permits the oil-cup to be drained to the very bottom.

In most oil-cups heretofore made the cup and stem by which it is screwed to the machinery are cast in one piece and are both made of brass. We have found it to be of advantage to make the cup of brass; but the interior stem, by which the cup is held in place and through which the oil is fed to the bearing, we make of wrought-iron or steel. This greatly strengthens the mechanism and makes it difficult to knock it off or remove it. The cap of my oil-cup is solid and has no apertures in it. It is screwed tightly upon the cup and prevents the escape of oil. This is an advantage over other cups which have parts of the mechanism protruding through the top of the cup for adjustment of the feed.

35 Having thus described our invention, what

we claim, and desire to secure by Letters Patent, is—

1. The combination of an oil-cup with an independent central stem passing through the oil-cup and whereby it is secured to the machine to be lubricated, having a hole through its center, within which is a vibrating valve for controlling the flow of oil to the bearing, an adjustable cap consisting of a cylindrical portion which is screwed upon the top of the central stem, and a yoke passing from one side to the other across the top of the valve-stem, whereby the throw of said stem is limited.

2. The combination of an oil-cup with an independent central stem passing through the oil-cup and whereby it is secured to the machine to be lubricated, having a hole through its center, within which is a vibrating valve for controlling the flow of oil to the bearing, an adjustable cap consisting of a cylindrical portion which is split at one point, so as to be tightened or expanded by pressure, and a yoke passing across the top from side to side, the under side of the interior of which is in proximity to the top of the valve-stem, whereby the throw of the valve-stem is limited.

Signed at Baltimore city and State of Maryland this 2d day of March A. D. 1892.

FRANCIS JOHN COLE.
GEORGE BLAGDEN HAZLEHURST.
